UNITED STATES PATENT OFFICE.

GEORGE M. CHENEY, OF INDIANAPOLIS, INDIANA.

BRIDGE CONSTRUCTION.

SPECIFICATION forming part of Letters Patent No. 708,463, dated September 2, 1902.

Application filed February 24, 1902. Serial No. 95,252. (No model.)

To all whom it may concern:

Be it known that I, GEORGE M. CHENEY, a citizen of the United States, residing at Indianapolis, in the county of Marion and State 5 of Indiana, have invented certain new and useful Improvements in Bridge Construction, of which the following is a specification.

My invention relates to an improvement in the structure of and the means for erecting 10 arch bridges or culverts composed partially of cement.

The object of my invention is to provide a frame which may be first accurately and easily set in any desired position for the production 15 of cement abutments and wing-walls, to provide an improved arrangement of struts for transmitting the stresses from the center of the arch to the abutments, to provide means for supporting the necessary false work upon 20 the superstructure, and to provide such improvements in the details of construction as shall be hereinafter pointed out.

The accompanying drawings illustrate my invention.

25 Figure 1 is a perspective view showing the abutment and wing-wall skeletons and the skeleton superstructure supported thereby. Fig. 2 is a transverse section. Fig. 3 is a detail of the false-work support. Fig. 4 is a 30 sectional detail.

In the drawings I have indicated a pair of opposed abutment frames or skeletons, each of which is composed of a plurality of angle-irons or suitable metallic strips 5, which 35 form an open box-like body, and leading from each end of the abutment-frame thus formed is a wing-wall frame which is formed of a series of angle-irons 6. The angle-irons 5 and 6 form an open box or frame into which 40 may be introduced a cement filling, which when it hardens will incorporate the metallic frame as a portion of the completed abutment and attached wing-walls. The abutment-frame is braced at its middle with a bracing-frame 7, and extending from said frame in opposite directions are two brace-rods 8, each of which is secured at its outer end to one of the wing-wall frames, preferably at the upper corner, as shown in Fig. 1. The 45 combined abutment and wing-wall frame thus formed may be readily and accurately adjusted and brought to an exact position. As

soon as this is done suitable planking may be placed along the open sides of this frame and a cement filling placed therein, the framework thus becoming incorporated in the structure and forming the marginal lines of the completed abutment and wing-walls. 55

Resting upon the angle-iron which forms the upper water corner of each abutment is 60 a channel-iron 9, to the ends of which are secured suitable end trusses 10. Extending between the centers of the end trusses 10 is a beam 11, preferably latticed, and when the arch is of considerable length intermediate 65 beams 12 12 will extend between the two end trusses 10. In order to distribute the stresses from the center of the arch to the channel-irons 9, I spring midway between the two end frames 10 a strut 13, which may be a single 70 bar secured to the beams 11 and 12 or may be made of several pieces, each extending from one beam to another and from each channel-iron to the adjacent beam. Extending from each beam 12 to the adjacent channel-iron 9 75 are supplemental struts 14. If the arch be divided into more than four panels, as shown, each succeeding panel away from the center beam will be provided with an increasing number of struts, so that the total load may 80 be evenly distributed upon the abutment.

The structure described is particularly designed for the construction of bridges or arches composed largely of cement, and it has heretofore been the custom to support the 85 false work necessary for the temporary holding of the cement composing the arch by staging supported from the bed of the stream. In my present construction this false work is supported from the superstructure, and in 90 order that the supporting-bolts may be removed without injuring the cement I proceed in the following manner: The false work is composed of a plurality of supporting-platforms 20, which together form the length of 95 the arch and are adapted to be supported immediately beneath the struts 13 and 14, the platforms being divided, preferably along a line adjacent one of the beams 11 or 12, the point of division being opposite the beam 11 100 in the structure indicated in the drawings. Beneath the adjacent ends of the platform 20 I arrange a bar 21, which is supported by means of a strap 22 and two or more bolts 23,

the said bolts being supported by a strap 24, placed across the beam 11. Surrounding each bolt and resting upon the platform is a tube 25, which in internal dimension is slightly 5 greater than the diameter of the bolt and in length is substantially equal to the thickness of cement or other filling which is to be laid upon the platforms 20. In placing the filling in position the tubes 25 are embedded 10 therein; but as soon as the filling has hardened bolts 23 may be readily withdrawn without disturbing the filling in any manner and the false work thus removed. A similar construction may be used in supporting 15 the temporary sides of the abutment-frames, the sides 26 being held in position by means of bolts 27, which will pass entirely through the frame and be surrounded by tubes 28, which will become embedded in the cement. 20 After the bolts have been withdrawn the tubes may or may not be filled with cement, as desired.

I claim as my invention—

1. A combined abutment and wing-walls 25 consisting of a metallic framework approxi-

mating the desired form of abutment and attached wing-walls and adapted to contain and be embedded in cement.

2. A combined abutment and wing-walls 30 consisting of a metallic framework approximating the marginal lines thereof, an intermediate bracing-frame forming part of the abutment-frame, and tie-rods extending from said bracing-frame to the ends of said wing-wall frames, the whole adapted to receive and 35 be embedded in cement.

3. In a bridge structure, the combination 40 with the end trusses, of a plurality of beams extending between and connected to the same, and a plurality of struts extending between the several beams parallel with the end trusses and increasing in number from the center of the arch toward each end.

In witness whereof I have hereunto set my hand and seal at Indianapolis, Indiana, this 45 17th day of February, A. D. 1902.

GEORGE M. CHENEY. [L. s.]
